UNITED STATES PATENT OFFICE.

NICHOLAS S. VEDDER AND FRANCIS RITCHIE, OF TROY, AND TOBIAS S. HEISTER, OF LANSINGBURG, ASSIGNEES TO NICHOLAS S. VEDDER, OF TROY, NEW YORK.

DESIGN FOR AN OVEN PARLOR-STOVE.

Specification forming part of Design No. 6,315, dated December 17, 1872.

To all whom it may concern:

Be it known that we, NICHOLAS S. VEDDER and FRANCIS RITCHIE, of the city of Troy, in the county of Rensselaer and State of New York, and TOBIAS S. HEISTER, of Lansingburg, in the said county and State, have jointly invented and produced a new and original Design for Oven Parlor-Stoves, of which the following is a specification, reference being had to the accompanying wood cut or engraving of a stove which embodies our said design.

One part of our invention consists of the compound ornament *m*, shaped and arranged on a door or panel of a stove substantially as shown in the aforesaid wood-cut. Another part consists of the compound ornament *n*, shaped and arranged on a door or panel of a stove as shown in the aforesaid wood-engraving. Another part consists of the ornamented compound molding or moldings *o*, shaped and arranged along the edges of a door or doors or panel or panels of a stove substantially as shown in the cut. Another part consists in the combination of the ornament *m* and molding *o*, as shown in the engraving. Another part consists of the combination of the molding *o* and ornament *n* or *p*, as shown in the cut, with or without the beading *q* or *q'*. Another part consists of the design for the hearth

R, as distinguished by the rim *S*, shaped and ornamented as shown in the cut. Another part consists of the design for the front plate *T*, as distinguished by the beading ornamentations *u*, *v*, and *w*, all shaped and arranged on the plate as shown in the engraving. Another part consists of the design for the leg or legs *X*, as shown in the cut.

What we claim as our invention is—

1. The ornament *m*, shaped and arranged as described.
2. The ornament *n*, shaped and arranged as set forth.
3. The ornamented compound molding *o*, shaped and arranged as herein set forth.
4. The combination of the ornament *m* and molding *o*, as set forth.
5. The combination of the molding *o* and ornament *n* or *p*, as set forth.
6. The design for the hearth *R*, as described.
7. The design for the front plate *T*, as set forth.
8. The design for the leg or legs *X*, as shown.
